A. B. Nims

UNITED STATES PATENT OFFICE.

A. B. NIMBS, OF BUFFALO, NEW YORK, ASSIGNOR TO HIMSELF AND J. C. CLIFFORD, OF SAME PLACE.

IMPROVEMENT IN THE MANUFACTURE OF ELEVATOR-BUCKETS.

Specification forming part of Letters Patent No. 42,734, dated May 10, 1864.

To all whom it may concern:

Be it known that I, A. B. NIMBS, of the city of Buffalo, county of Erie, and State of New York, assignor to A. B. NIMBS and J. C. CLIFFORD, have invented certain new and Improved Elevator-Buckets; and I do hereby declare that the following is a full, clear, and exact description thereof, reference being had to the accompanying drawings and the letters of reference marked thereon, in which—

Figure I is a vertical cross-section of my improved bucket; Fig. II, a front elevation of the same. Fig. III is a detail section showing the manner of fastening the front to the ends of the bucket, and Fig. IV represents the bucket spread out or developed upon a plane surface.

This invention consists in forming an elevator-bucket with the band around its upper edge of one sheet or piece of metal, which is cheap, strong, and durable.

Letters of like name and kind refer to like parts in each of the figures.

A represents the back or vertical side through the holes a' , in which the bolts which secure the bucket to the elevating-belt pass.

B represents the curved front or dipping side of the bucket.

C represents the ends of the bucket, to which the curved front is fastened by a double lock-joint, c' . (Shown in section in Fig. III.)

D represents a broad band or belt passing around the upper edge of the bucket and giving strength and stiffness to the same.

By a reference to the developed plan, Fig. IV, and the following description the formation of the bucket, with the stiffening-band, will be readily understood. The end pieces, C,

are turned upon the line c^2 as an axis until their surface is at right angles to the surface of the back A. The front B is then turned upon the line b' as an axis (at the same time being given its proper convexity) until it meets the end pieces, C, to which it is secured by the double lock-joint c' , (shown in Fig. III,) the leaves c^3 and b^3 giving the necessary metal for the formation of the joint. The band D on the end pieces is then turned down upon the line c^5 for an axis until they meet the end pieces, its edge being turned again on the line c^6 . The band D on the back A is turned down on the line a^2 for an axis, and is turned or doubled under on the line a^3 . The earlaps a^4 lap around onto the end pieces, C, and are secured by the rivets a^5 . The band D on the front is turned down on the line b^2 and turned or doubled under on the line b^6 . The earlaps b^4 lap around onto the end pieces, C, as seen in Figs. I and II, and are secured by the rivets b^5 .

E represents a brace running through the center of the bucket, and riveted to the front and back, as shown at $e' e^2$. There being no joints in this bucket which require soldering, it may be made of sheet-iron, which material makes a much stronger, cheaper, and more durable bucket than the tin ones now in use.

I claim—

An elevator-bucket, with its strengthening-band, constructed and formed from one sheet or piece of metal, substantially as herein described.

A. B. NIMBS.
